CLAIM

The ornamental design for a threaded tree support bolt with adjustable knob, as shown and described.

DESCRIPTION

FIG. 1 is a top front perspective view of a threaded tree support bolt with adjustable knob, showing our design;
 FIG. 2 is a front elevation view thereof;
 FIG. 3 is a left side elevation view thereof;
 FIG. 4 is a right side elevation view thereof;
 FIG. 5 is a top front perspective view of a second embodiment of a threaded tree support bolt with adjustable knob;
 FIG. 6 is a front elevational view thereof;
 FIG. 7 is a left side elevation view thereof; and,
 FIG. 8 is a right side elevation view thereof.
